United States Patent Office

Des. 187,841
Patented May 3, 1960

187,841

PLASTIC SHEET MATERIAL OR THE LIKE

Hill Borrow, London, England, assignor to Duraplex
Plastics Limited, London, England

Application June 24, 1959, Serial No. 56,521

Claims priority, application Great Britain
February 12, 1959

Term of patent 3½ years

(Cl. D87—3)

The figure is a plan view of a plastic sheet material, showing my new design.

A unit is enclosed within the dot and dash lines on the drawing which unit is repeated in regular succession as indicated by the extensions beyond the unit boundaries.

I claim:

The ornamental design for a plastic sheet material or the like, as shown.
